SCREW CONVEYER AND THE LIKE HAVING
INTERRUPTED FLIGHTSHjalmar S. Messing, New York, N. Y., assignor to
American Defibrator Inc., New York, N. Y., a
corporation of New York

Application August 16, 1951, Serial No. 242,155

3 Claims. (Cl. 198—213)

1. This invention relates to defibrators such as are usually employed for the production of pulp from ligno-cellulose materials, such as wood chips, an example of such apparatus being found in the patent to Asplund No. 2,145,851, dated February 7, 1939, and to other devices in which spiral conveyors may be advantageously employed.

In such an apparatus as shown in the Asplund patent is employed a screw conveyor which operates to provide a uniform flow of material through the apparatus and as known at the present time, such conveyors are usually in the form of a spiral screw feed, having in some cases, a continuous flight, and in other cases interrupted flights. It has been found that with the use of a continuous flight on the conveyor, or even with the employment of uniform-diameter interrupted flights thereon, the preheated chamber in which the conveyor is operative frequently becomes clogged. This especially occurs when the defibrator is employed for the processing of wood chips, bark, sawdust and other wet, pitchy and gummy materials.

It is therefore an object of the present invention to provide a screw conveyor particularly adapted for use in connection with the above materials and in which a marked increase in the filling up of the available space in the preheater will result. It is another object of the invention to provide an interrupted flight screw which produces a stirring effect on the material; which will relieve pressure on the peripheral portion of the plug of material that is being moved ahead and this serves to prevent clogging of the pipe and causes the material to fill and preheat the preheating chamber uniformly.

These and other objects are attained by the invention, a more particular description of which will hereinafter appear and be set forth in the claims appended hereto.

In the accompanying drawing, wherein an illustrative embodiment of the invention is disclosed, Fig. 1 is a longitudinal sectional view through a screw conveyor constructed in accordance with the invention;

Fig. 2 is a sectional view taken substantially on the line 2—2 of Fig. 1, looking in the direction of the arrows, and

Fig. 3 is a sectional view taken substantially on the line 3—3 of Fig. 1, looking in the direction of the arrows.

In the embodiment shown in the drawing, 10 indicates a feed chamber of substantially cylindrical form into which the material to be treated

50 enters from a hopper or other suitable source of supply by means of the inlet opening 11. The feed screw includes the rotatable shaft 12 carrying the interrupted flights to be described.

The shaft is rotatably supported at its opposite ends in the bearings 13 and 14, which are suitably packed to prevent leakage at these points.

In the construction as illustrated in the drawing, and starting at the left end of the structure shown in Fig. 1, one of the flights at that end of the shaft 12 is indicated at 4. Starting at the point 4b, adjacent to the shaft 12, this flight gradually increases in radius until it reaches its maximum and then sharply terminates as indicated at 4a. The next flight, or that indicated at 3, begins at shaft 12 as indicated at 3b and then gradually increases in radius but does not reach a radius as great as the maximum radius of the flight 4, and terminates sharply as indicated by the end point 3a. The flight shown at 2, which is next on the shaft 12, begins at the shaft at the point designated at 2b and increases in radius to its maximum, and which corresponds in diameter to the maximum diameter of the flight 4. The flight shown at 1 corresponds in diameter to that shown at 3, the same starting at the point 1b, and then increasing to its maximum diameter, which is less than that of the flights 2 and 4, and then sharply terminating at the point 1a. The flights thereafter provided along the shaft may be repeats of those described, or the flights may alternate in various ways, to not only best secure a positive and uniform feeding of the material, but to mix or agitate the same while it is being fed.

In operation, the material is delivered into the chamber 10 through the inlet opening 11 from a suitable source such as from a hopper connected to the inlet 11 and from which the material is fed by any positive feed means. As the material enters into the chamber 10 it is fed along toward the right by the flights to finally enter between the propelling blades 17 on the shaft 12, forcing the material toward and into the outlet 18. The action of directing the material into the outlet 18 is facilitated by the disc 19 mounted on the shaft 12 and which is provided with projecting pins or fingers 20.

The shaft 12 is rotatably driven from a motor or other power source operative to rotate the shaft by means engaging the extended end portion of the shaft indicated at 21 and located externally of the chamber 10.

In the arrangement of the several separate

flights mounted on the shaft 12, it is preferred that succeeding flights do not truly follow the pitch of the preceding flight but are off-set. It is to be noted that each flight begins as a new screw and increase in radius to its maximum and then abruptly terminates at the beginning of the next flight, and this results in each new flight picking up and forcing the material forwardly through the chamber.

While I have herein shown and described one embodiment of the invention, it is apparent that various modifications may be made without departing from the spirit of the invention. For example, while I have herein shown the several flights on the shaft arranged and disposed in a certain sequence, it will be apparent that the same may be otherwise arranged to secure results possibly found more effective when different types of material is being treated. In addition the chamber, its inlet and outlet openings and other elements may be varied according to the particular apparatus in which the feeder is used. Therefore, since such modifications may be made in the structure described without departing from the scope thereof, it is intended that all matter contained in the foregoing specification and shown in the accompanying drawing shall be interpreted merely as illustrative and not in a limiting sense.

What I claim is:

1. In an apparatus of the character described, a chamber, a screw feeder rotatively mounted therein, said feeder including a shaft, a flight thereon of gradually increasing radius to reach a maximum closely conforming to the interior diameter of the chamber, a second flight on the shaft, said second flight starting of small radius

adjacent to the shaft and gradually increasing its radius to a maximum of considerably less radius than the maximum of the first flight, and with this sequence of flights repeated along the length of the shaft.

2. In an apparatus of the character described, a chamber, a shaft rotatively mounted in said chamber, said shaft being provided with a plurality of independent flights arranged upon it, each flight having an end located closely adjacent to the shaft, with the flight gradually increasing in diameter to its opposite end, said opposite end terminating on a line extending radially from the shaft, each flight starting adjacent to the end of the flight which preceded it.

3. In an apparatus as provided for in claim 2, wherein some of the flights are of lesser maximum diameter than others, with said flights of lesser diameter being located intermediate of those of the greater diameter.

HJALMAR S. MESSING.
